DESCRIPTION

FIG. 1 is a top plan view of a closure clip unit showing
my new design, the bottom plan view being a mirror
image thereof;

FIG. 2 is a front elevational view;

FIG. 3 is a rear elevational view; and,

FIG. 4 is a right side elevational view, the left side being
a mirror image thereof.

The closure clip unit is shown broken away at the ends
to indicate indeterminate length.

FIG. 1

FIG. 2

FIG. 3

FIG. 4
